UNITED STATES PATENT OFFICE.

HAROLD P. BAILEY, OF FRANKLIN, NEW HAMPSHIRE.

WATCH-BOW.

1,348,388.

Specification of Letters Patent.

Patented Aug. 3, 1920.

Application filed October 15, 1919. Serial No. 330,777.

To all whom it may concern:

Be it known that I, HAROLD P. BAILEY, a citizen of the United States, residing at Franklin, in the county of Merrimack, State 5 of New Hampshire, have invented certain new and useful Improvements in Watch-Bows; and I do hereby declare the following to be a full, clear, and exact description of the invention, such as will enable others skilled in the art to which it appertains to 10 make and use the same.

This invention relates to watch case pendants, and more especially to bow fasteners including a sleeve; and the object of the 15 invention is to mount the bow on the pendant in such manner that when the bow stands in its normal position and substantially in the plane of the case, the outer bar of the bow closely overlies the crown 20 of the stem so that it may not be drawn outward and turned through accident and thus set the watch without the knowledge of the wearer.

The invention is applicable more especially to wrist watches, because the strap leading from the bottom of the case around the wrist to the bow will hold the latter in the plane mentioned, and therefore accidental setting of the watch is impossible if it 30 be of that type wherein the stem must be drawn outward to effect setting.

The following specification sets forth so much of the details as are necessary to a clear understanding of this invention, reference being had to the drawings wherein:

Figure 1 is a plan view of a watch embodying this invention, strapped to the back of the left wrist.

Fig. 2 is an enlarged section in the plane 40 of the watch, taken through the pendant and the parts attached thereto, and

Fig. 3 is a similar section in a plane at right angles to that of Fig. 2.

As this invention is intended to be applied to a wrist watch, the case 1 has at its bottom a loop 2. Also it is provided at its top with an upstanding tubular pendant 3 externally threaded at 4 around its tip and shouldered at 5 around its base next the 50 case. Through this pendant is mounted the stem 6 which must be rotated to wind the

watch and drawn outward and turned to set the watch, and the outer end of the stem carries a knurled knob or crown 7.

Loosely mounted around the pendant is 55 a sleeve 10 having sockets 11 in opposite sides into which are sprung and within which are pivotally mounted the extremities of a split ring which constitutes the bow 12, the size or shape of this bow being such that in its usual and normal position where it lies in the plane of the watch its outer side or cross bar rather closely overlies the crown 7. The result is that the latter may not be moved outward to set the watch, unless the 60 bow is first swung aside where it is pivotally mounted in the sockets 11. Finally a threaded washer or nut 14 is screwed onto the threads 4 of the pendant to hold the sleeve 10 in place. When now a strap 15 65 leads from the loop 2 around the wrist and is connected with the bow and tightened up, the bow will be held by the strap in such position that its cross bar overlies the crown 70 and extends almost across its center, depending on the size of the watch and the wearer's 75 wrist and the shape of the back of the latter. Upon removing the watch from the wrist at any time, the bow can be swung aside and the crown manipulated for winding or setting.

What is claimed is:

In a watch, the combination with a case, a tubular pendant projecting therefrom and threaded around its outer end and having 85 an outwardly facing shoulder near its inner end, and the setting mechanism including a stem projecting through the pendant and having a crown at its outer end; of a nut on said threads beneath the crown, a sleeve 90 revolvably mounted on the pendant between its shoulder and said nut, the sleeve having sockets in its opposite sides, and a bow consisting of a split ring whose extremities are mounted in said sockets.

In testimony whereof I affix my signature in the presence of two witnesses.

HAROLD P. BAILEY.
